Inventor

Louis Marville.

UNITED STATES PATENT OFFICE.

LOUIS MABILLE, OF NEW YORK, N. Y.

WATCHCASE.

Specification of Letters Patent No. 23,085, dated February 22, 1859.

To all whom it may concern:

Be it known that I, LOUIS MABILLE, of the city, county and State of New York, have invented a new and useful Improvement 5 in Watchcases; and I do hereby declare that the following is a full, clear, and exact description of the same, reference being had to the accompanying drawing, forming part of the specification, in which—

10 Figure 1, is a front view of a watch case with my improvement. Figs. 2 and 3 are central sections of the same, the former representing it as a hunting watch case, and the latter with an open front. Fig. 4, represents the case with the back open and with 15 the inside of the back toward the spectator.

Similar letters of reference indicate corresponding parts in the several figures.

This invention consists in a certain novel 20 construction of what is known as a "magic" watch case, whereby extreme simplicity is combined with neatness of appearance.

To enable others skilled in the art to make and use my invention, I will proceed 25 to describe its construction and operation.

A, is the principal portion or band of the case, which contains the movement, and has the handle b, permanently attached.

B, is the back, hinged to A, in the usual 30 manner, by a hinge c.

a, is the ring or frame which contains the glass l, hinged to the part A, of the case, in the same manner as in an ordinary hunting watch.

35 C D, is the front of the case, made in two pieces, which, when combined, as shown in the section, Fig. 3, present a similar appearance to the front of the case of an ordinary hunting watch. These two pieces 40 consist of a ring or frame C, which is hinged at h, to the part A, in the same manner as the front of a hunting watch case, and a circular plate D, to cover the opening in the said ring or frame, which

45 opening is of about the size of the watch face or dial. The ring or frame C, and the plate D, are attached together by providing a very small raised rim e, see Figs. 2 and 3, on the outer face of the inner 50 margin of the ring or frame C, to be received within a shallow bezel i, which is

formed around the inner face of the margin of the plate D, the said rim e, and bezel i, being slightly dovetailed to provide for the secure attachment of the plate D, to 55 the ring or frame C, and the plate D, having its marginal portion sufficiently concave to give it the requisite slight degree of elasticity which is desirable, to make the said plate secure when on the ring or frame 60 C, and yet to provide for its slipping on and off the rim e, when desired.

The plate D, is easily removed from the ring or frame C, when the front C D, of the case is open, by holding the ring C, at 65 opposite sides between the thumbs and fingers of both hands, and with the thumbs or fingers pressing the plate D, outward from the ring or frame. The ring being then closed on the part A, of the case, as shown 70 in Fig. 2, the watch presents the same appearance as an open faced watch, the rim e, projecting so little as to be unobservable except by close examination.

To provide convenience for carrying the 75 plate D, at the back of the watch case, when it is removed from the front thereof, I provide a cavity d, d, see Fig. 3, in the interior of the back B, of a form to receive the said plate D, without its interfering with the 80 shutting up of the back. On one side of this cavity there is a projecting stationary catch f, see Figs. 2, 3, and 4, under which the edge of the plate D, is placed, and on the opposite side there is a spring catch g, which 85 springs aside to admit the said plate into the cavity when the latter is pressed against it, and springs over the edge of the plate in the manner illustrated in Figs. 2 and 4, after the plate is inserted in the cavity, and 90 thus secures it therein. When it is desired to remove the plate D, from the cavity d, d, the spring catch g, is pushed back off it, and it is allowed to drop out.

This method of constructing the case gives 95 it a neat appearance on the exterior in either of its conditions, and makes it present a similar neat appearance to a common case, and neither materially increases the depth of the case or thickness of the watch, nor 100 presents any knobs, catches, or other projections on the exterior of the case.

I do not claim the movable plate D, when applied and fitted to, and combined with the case otherwise than as herein described. But

5 What I claim as my invention, and desire to secure by Letters Patent, is—

The construction of the case substantially as herein described, with the front plate D, fitted to the ring or frame C, with a project-

ing rim e, and bezel i, all the way around 10 when combined with an internal cavity d, d, in the back to receive and contain the said plate when removed from the front.

LOUIS MABILLE.
